5 Claims. (Cl. 62—28)

ABSTRACT OF THE DISCLOSURE

A method of separating the heavier hydrocarbons from liquefied natural gas in a fractionating zone which includes introducing into the upper part of the fractionating zone hydrocarbons heavier than C_2 which have been cooled by heat exchange with liquid natural gas being fed to the fractionating zone.

This invention relates to a method of separating the heavier hydrocarbons from liquefied natural gas containing a substantial proportion of methane.

A method of this kind is the subject of British patent specification No. 854,099, corresponding to U.S. Patent No. 2,952,984, in which the method claimed comprises the steps of:

(a) Feeding the liquefied natural gas at superatmospheric pressure into the medial portion of a fractionating zone;

(b) Heating the contents of the lower portion of the fractionating zone to a temperature to produce methane enriched vapors in the upper portion of the fractionating zone;

(c) Withdrawing vapors from the upper portion of the fractionating zone and passing said vapors in heat exchange relation with the liquefied natural gas being fed to the fractionating zone, to heat said feed and cool said vapors;

(d) Separating condensates from said vapors;

(e) Refluxing said condensates to the upper portion of the fractionating zone for cooling the upper portion of the fractionating zone and inducing downward movement of heavier hydrocarbon enriched liquefied gas into the lower portion of the fractionating zone; and

(f) Withdrawing the heavier hydrocarbon enriched liquefied gas from the lower portion of the fractionating zone.

In the above method the heavier hydrocarbons and the methane are separated from one another in an efficient manner by making use of the cold which is available in the liquefied natural gas, while simultaneously the liquefied natural gas is regasified for its further use after having served as a refrigerant.

The present invention relates to an improvement of the method of British patent specification No. 854,099, whereby a larger proportion of the methane and a smaller proportion of the heavier hydrocarbons supplied to the fractionating zone in the liquefied natural gas feed may be withdrawn from the top of the fractionating zone, and correspondingly, a smaller proportion of the methane and a larger proportion of the heavier hydrocarbons originally in the liquefied natural gas feed leave the fractionating zone as a bottom product.

According to the present invention, the above method of separating the heavier hydrocarbons from liquefied natural gas containing a substantial proportion of methane comprises the additional step of introducing a C_3

2

and/or heavier hydrocarbon material into the upper portion of the fractionating zone.

The method of the invention will be explained further by way of example with reference to the accompanying drawing, which represents a flow scheme for this method.

In the drawing the liquefied natural gas is supplied to the medial zone of a fractionator or demethaniser 10 through line 11. The liquefied natural gas before being introduced into line 11 has already been allowed to flash off some of its lighter components, and the composition of the liquefied natural gas which is fed to the demethaniser 10 is as follows:

	Mol per hour	Mol percent
15 C_1 hydrocarbons-----	631.1	37.1
C_2 hydrocarbons-----	514.0	30.2
C_3 hydrocarbons-----	403.9	23.7
C_4 hydrocarbons-----	153.2	9.0
	1,702.2	100.0

It will be understood that this composition is an example only and that the liquefied natural gas which is processed in the demethaniser 10 may have many different compositions.

The liquefied gas is introduced into line 11 at a temperature of -85° F. and a pressure of about 210 p.s.i.a. Upon passing through a heat exchanger 14 the temperature of the liquefied gas rises to -70° F., and after passing through another heat exchanger 15, the temperature has increased to -55° F. At this temperature of -55° F. the liquefied gas is introduced as feed to the medial zone of the demethaniser 10. In the demethaniser 10, which operates at 185 p.s.i.a., the feed is heated and thereby separated into a top fraction consisting of methane enriched vapors and a bottom product containing the heavier hydrocarbons. The bottom temperature of the demethaniser 10 is maintained at 54° F. The reboiler circuit used for heating the demethaniser 10 is shown at 10a. Valve controls for the bottom products of columns 29 and 12 are shown at 26a and 28a respectively. All pumps, valves, etc., not necessary to understand the method of the invention have been left out of the drawing.

The composition of the vapors leaving the top of the demethaniser 10 is as follows:

	Mol per hour	Mol percent
50 C_1 hydrocarbons-----	629.1	80.5
C_2 hydrocarbons-----	139.2	17.8
C_3 hydrocarbons-----	1.0	0.1
C_4 hydrocarbons-----	12.2	1.6
	781.5	100.0

Attention is drawn to the fact that the quantity of methane in these overhead vapors is 99.7% of the quantity of methane in the feed to the demethaniser 10. The vapors are withdrawn from the demethaniser 10 through line 17. Before the vapors subsequently pass in heat exchange with the liquefied natural gas in heat exchanger 14 they are joined with a stream of C_4 hydrocarbons being at a temperature of -30° F. and flowing to line 17 through line 23. The combined stream of methane enriched vapors and C_4 hydrocarbons now passes through the heat exchanger 14, whereby the vapors are cooled and partly condensed. The condensates from the vapors are collected in a reflux vessel 18, from where the condensates together with the C_4 hydrocarbons are conducted to the top of the demethaniser 10 through line 19. In

the demethaniser 10 the C₄ hydrocarbons serve as a refrigerant to cool the top of the demethaniser and as an absorption liquid to remove the C₂ and heavier hydrocarbons from the vapors leaving the demethaniser 10.

It will be understood that the C₄ hydrocarbons could have been introduced immediately into the top of the demethaniser 10 through line 23a, or into line 17 between the heat exchanger 14 and the reflux vessel 18 through line 23b if the temperature of the C₄ hydrocarbons in line 23 had already been at a desired level. However, the introduction into line 17 upstream of the heat exchanger 14 is normally to be preferred.

The temperature of the liquids collected in the reflux vessel 18 and passed to the demethaniser 10 is about -30° F. to maintain a temperature of -20° F. in the top portion of the demethaniser 10.

The methane enriched vapors separated from the condensates in the reflux vessel 18 leaves the top of the reflux vessel 18 through line 29 and pass through a series of heat exchangers 21 to usefully abstract heat from these vapors which are being warmed up from -30° F. to a temperature of about 60° F. The methane vapors, which are at about 157 p.s.i.a., are now discharged from the system and may be distributed as fuel gas. The product formed in the bottom of the demethaniser 10 is drawn off and passed through line 22 as a feed to a second fractionator 29, which operates as a de-ethaniser.

The composition of the bottom product of the demethaniser 10 is as follows:

	Mol per hour	Mol percent
C ₁ hydrocarbons-----	2.0	0.2
C ₂ hydrocarbons-----	374.8	34.5
C ₃ hydrocarbons-----	402.9	37.1
C ₄ hydrocarbons-----	305.5	28.2
	1,085.2	100.0

Thus, the quantity of methane retained in the bottom product is only 0.3% of the total quantity of methane supplied to the demethaniser 10.

The de-ethaniser 29 is maintained at a pressure of 170 p.s.i.a. and at a bottom temperature of about 120° F. Under these conditions the feed of the de-ethaniser 29 is fractionated into a top fraction which consists mainly of C₂ hydrocarbons and a bottom fraction containing C₃ and heavier hydrocarbons. The C₂ hydrocarbons are withdrawn from the de-ethaniser 29 through line 24 and pass on to a cracking plant 13.

The bottom fraction is drawn off from the de-ethaniser 29 through line 26 and is fed to still another fractionator 12, which acts as a depropaniser. The depropaniser 12 operates under 188 p.s.i.a. and at a bottom temperature of 200° F. The top fraction which consists substantially of C₃ hydrocarbons passes from the depropaniser 12 through line 25 to the cracking plant 13. Likewise, a portion of the bottom fraction of substantially C₄ hydrocarbons is drawn off through line 27 also to the cracking plant 13. In the cracking plant 13 the hydrocarbons supplied thereto through lines 24, 25 and 27 are thermally cracked, quenched, compressed, washed and hydrogenated in a conventional manner to produce a mixture of gases which can be separated into a number of individual products, including further methane gas. The other portion of the C₄ hydrocarbons leaving the bottom of the depropaniser 12 is not delivered to the cracking plant 13 but passes through line 28 and a heat exchanger 16. In the heat exchanger 16 the C₄ hydrocarbons flowing therethrough are cooled by cooling water to a temperature of 100° F. The C₄ hydrocarbons are subsequently passed through heat exchanger 15 in heat exchange with the liquefied natural gas flowing through line 11, whereby the temperature of the C₄ hydrocarbons is further low-

ered to about -30° F. At this temperature the C₄ hydrocarbons are discharged through line 23 into line 17.

As explained, a portion of the C₄ hydrocarbons drawn off from the bottom of the depropaniser 12 is sent to the top of the demethaniser 10, while the remaining portion passes to the cracking plant 13. Instead, all of the C₄ hydrocarbons may be conducted to the cracking plant 13, and a portion of the bottom product from the de-ethaniser 29 consisting of C₃ and C₄ hydrocarbons may be drawn off from line 26 and passed into line 28 through valve 26a to be cooled in the heat exchangers 16 and 15 subsequently to be discharged into line 17 for introduction into the demethaniser 10. Alternatively, in certain circumstances, it may be preferred to separate C₂ and C₃ hydrocarbons together as a top product in the second fractionator 29, C₄ hydrocarbons being produced as a bottom product which is either passed to the demethaniser 10 or cracked in the cracking plant 13. The C₂ and C₃ hydrocarbon mixture would either be separated by subsequent fractionation or be cracked. Still alternatively, C₃ or C₅ hydrocarbons alone or a mixture of hydrocarbons heavier than C₂ hydrocarbons may be introduced into the demethaniser 10, or the hydrocarbons to be administered to the demethaniser 10 may be supplied by sources other than the de-ethaniser 29 or the depropaniser 12. For example, C₃ and/or C₄ hydrocarbons may be separated from the mixture of gases produced in the cracking plant 13 and, after having been brought at the proper temperature and pressure level, be supplied wholly or partly to the demethaniser 10.

It will be apparent that the embodiments shown are only exemplary and that various modifications can be made in construction and arrangement within the scope of our invention as defined in the appended claims.

We claim:

1. In a method of separating the heavier hydrocarbons from liquefied natural gas containing a substantial proportion of methane, the steps of:

- (a) feeding the liquefied natural gas at superatmospheric pressure into the medial portion of a fractionating zone;
- (b) heating the contents of the lower portions of the fractionating zone to a temperature to produce methane enriched vapors in the upper portion of the fractionating zone;
- (c) withdrawing the vapors from the upper portion of the fractionating zone and passing said vapors in heat exchange relation with the liquefied natural gas being fed to the fractionating zone, to heat said feed and cool said vapors;
- (d) separating condensates from said vapors;
- (e) refluxing said condensates to the upper portion of the fractionating zone and inducing downward movement of heavier hydrocarbon enriched liquefied gas into the lower portion of the fractionating zone;
- (f) introducing at least one heavier hydrocarbon material heavier than C₂ into the upper portion of the fractionating zone; and
- (g) withdrawing the heavier hydrocarbon enriched liquefied gas from the lower portion of the fractionating zone;
- (h) passing the said hydrocarbon material before introduction into the fractionating zone in heat exchange with the liquefied natural gas being fed to the fractionating zone, to heat the liquefied natural gas and to cool the hydrocarbon material.

2. A method according to claim 1, wherein the liquefied natural gas being fed to the fractionating zone is passed in heat exchange with the said hydrocarbon material after having passed in heat exchange with the vapors withdrawn from the top of the fractionating zone.

3. A method according to claim 2, wherein the said hydrocarbon material is introduced into the reflux circuit of the fractionating zone through which the methane enriched vapors are withdrawn from, and the con-

densates from these vapours are returned to, the fractionating zone.

4. A method according to claim 3, wherein the said hydrocarbon material is discharged into the reflux circuit at a point before the methane enriched vapours pass in heat exchange with the liquefied natural gas being fed to the fractionating zone.

5. A method according to claim 4, wherein the heavier hydrocarbon enriched liquefied gas from the lower portion of the fractionating zone is fed to at least one further fractionating zone to produce a bottom material containing heavier hydrocarbons than C_2 , at least a portion of this hydrocarbon material being introduced into the

5
10

upper portion of the fractionating zone producing the methane enriched vapours.
